UNITED STATES PATENT OFFICE.

SAMUEL J. SHIMER, OF MILTON, PENNSYLVANIA, ASSIGNOR TO SAMUEL J. SHIMER & SONS, OF SAME PLACE.

CUTTER-HEAD AND CUTTER-HEAD GAGE.

SPECIFICATION forming part of Letters Patent No. 380,530, dated April 3, 1883.

Application filed December 9, 1887. Serial No. 257,455. (No model.)

To all whom it may concern:

Be it known that I, SAMUEL J. SHIMER, a citizen of the United States of America, residing at Milton, in the county of Northumberland and State of Pennsylvania, have invented 5 a new and useful Gage for Cutter-Heads, of which the following is a specification.

My invention relates to improvements in means for determining the adjustment of the 10 bits or cutters of a cutter-head in either a lateral or vertical direction; and it consists in forming the cutter-head with angular grooves in the top and bottom faces, said grooves being arranged at an angle on the line with the 15 beveled faces of the cutters, and in a gage having graduated blade-lines to determine the adjustments by, and formed with projecting guides to slide in the grooves of the cutter-head.

20 I have fully illustrated my invention in the accompanying drawings, forming a part hereof, whereby—

Figure 1 represents a side view of a dado cutter-head having a bit secured therein and 25 my improved gage applied to adjust the cut of the bit. Fig. 2 is an end or plan view of the cutter-head, showing the arrangement of the gage-grooves and the gage applied. Fig. 3 is a perspective of my improved gage. Fig. 30 4 is a reverse view, and Fig. 5 an end view thereof.

Like parts appearing in the different figures of the drawings are designated by the same notations of reference.

35 A designates the cutter-head, having fixed and adjusted therein in operative position the bits or cutters B. The cutter-head shown in the drawings is of that character known in the trade as a "dado head," having the top and 40 bottom faces arranged on parallel planes and provided with vertically-arranged slots in the sides of the head, in which are fitted the means for clamping and holding the bits or cutters, substantially as shown.

45 It will be observed that my improvements are applicable to any cutter-head having parallel top and bottom faces and provided with bits horizontally movable or vertically adjustable, and therefore it is not deemed essential 50 to a proper understanding of my improve-

ments that a more specific description of the general features of the cutter-head be here given. In the top and bottom faces of the cutter-head are formed open-end slots or angular grooves 1, entering the body of the head just 55 in front of the chip-recess of each bit and arranged in the same relative direction as the bevel-line of the blade of the bit or cutter, and so that when the gage is set in position the face of the graduated portion of the gage shall 60 set against the beveled surface of the bit, as shown in Figs. 1 and 2 of the drawings.

B' designates my improved gage, substantially of the form shown in the drawings, and consisting of a metal plate having a central 65 piece, 2, on the face of which is indicated a scale of linear measurements, 3, and also parallel lines 4, arranged at right angles to the linear measurements. The former serve to measure the vertical adjustments of the respective bits and the latter serve to determine the projections of the bits in a horizontal direction. The ends of the central piece, 2, are extended at a plane about on a line with the under surface of the graduated part, as at 5, 70 and the extensions may be formed with ribs 6, to strengthen them and to afford a more convenient and ready hold for the hand. The parts 5 are also lengthened, as at 7, forming projections, lugs, or guide-pieces to slide and 75 fit within the grooves 1 when the gage is applied. This construction, it will be seen, admits of the gage being cut out in the under side, as at 8, so as to raise the measuring-face 80 up to the bit and bring the under surface clear 85 of the heel of the bit; but to avoid all interference with the heel of the bit the inner edge of the parts is beveled, as at 9. The graduated plate of the gage and its projecting lugs or guide-pieces 7 are arranged on lines parallel 90 with the same plane, so that the direction of the graduated part shall coincide with the direction of the guides when the gage is applied.

The gage is applied by sliding the guide-pieces 7 in the guide-slots 1 of the cutter-head until the gage is seated. The face of the gage will then set against the point of the bit, which may be adjusted by the graduations on the gage 95 in any desired direction and then clamped. 100

A repetition of the same act in respect to the remaining bits will effect an adjustment to a common cut in all.

What I claim is—

- 5 1. In combination with a cutter-head formed with guide-slots in the parallel top and bottom faces and a cutting-bit secured to the cutter-head, a gage comprised of a metal plate formed with a central piece having graduations 10 of measurements thereon, and formed with its ends extended and arranged below the upper face of the central piece, and guide-extensions arranged to register with and set within the guide-slots in the head, substantially as described.
- 15 2. A cutter-head formed with open-end gage-slots in the parallel top and bottom faces,

arranged in the direction of the line of the bevel of the cutting-bit for the reception of gage-supporting lugs, substantially as described.

3. The cutter-head gage herein described, consisting of the metal plate B', having a graduated central portion, 2, the end extensions, 5, arranged on a different plane parallel to the central portion, and the guide-pieces 7, to slide in open-end slots in the cutter-head, substantially as described, and for the purposes stated.

In testimony whereof I have hereunto set my hand in presence of two attesting witnesses.

SAMUEL J. SHIMER.
